F. A. WATKINS.
ELECTRIC WIRING SYSTEM.
APPLICATION FILED NOV. 5, 1915.

Patented Sept. 25, 1917.

1,240,907.

Inventor:
Frederick A. Watkins

By Gillies & Gillies Reg'd.

UNITED STATES PATENT OFFICE.

FRED. ICK A. WATKINS, OF CHICAGO, ILLINOIS.

ELECTRIC WIRING SYSTEM.

1,240,907.

Specification of Letters Patent. Patented Sept. 25, 1917.

Application filed November 5, 1915. Serial No. 59,850.

To all whom it may concern:

Be it known that I, FREDERICK A. WATKINS, a citizen of the United States, and resident of Chicago, county of Cook, and

5 State of Illinois, have invented certain new and useful Improvements in Electric Wiring Systems of which the following is a specification, and which are illustrated in the accompanying drawings, forming a part thereof.

10 The invention relates to electric wiring and more particularly to an arrangement of electrical conductors and fittings which may be installed as one piece for the illumination of show windows and the like, without the necessity of making other electrical connections than those which may be accomplished by the ordinary user, as for example the introduction of a switch plug into a socket. The object of the invention is to provide

20 a wiring system for electric illumination which is of simple and inexpensive construction, and is effectively safeguarded against the usual hazards pertaining to the transmission of electric current.

25 In the accompanying drawings,

Figure 1 is a side elevation showing one arrangement of the improved electric wiring system embodied in a window lighting fixture, some of the parts being shown in sec-

30 tion,

Fig. 2 is a detail longitudinal sectional view of the same,

Figs. 3 and 4 are plan views showing the meeting faces of two of the parts, details of 35 the electrical conductors being shown in Fig. 3,

Fig. 5 is a detail perspective view showing an element which may be employed for preventing rotation of the lamp fitting, and

40 Fig. 6 is a sectional view taken on the line 6-6 of Fig. 2.

The improved wiring system is more particularly useful for supplying current to a plurality of electric lamps, as 10, especially 45 when these lamps are to be arranged in a row, as for the illumination of show windows and the like. In such cases a metal tube, as 12, of rectangular cross section, is desirably employed to provide a support 50 for the parts, and a housing for the electrical conductors, as 14, 15. The ends of the tube 12 or 13 are closed by caps 18, 19, and one of these caps, as 19, has apertures fitted with insulated bushings 20 and 21, through 55 which the electrical conductors, as 14, 15, are extended. The free ends of the conduc-

tors 14, 15 are arranged for ready connection with a suitable source of electric energy, as by being fitted to a socket plug 22.

In practice the tubular holder 12 may be 60 suspended in any convenient manner, as by being secured directly against the wall or ceiling, or by being mounted in suitable brackets or hangers (not shown). In the form of construction illustrated, a plurality 65 of two part porcelain fittings 23, equal in number to the number of lamps to be served, are provided. One of the parts, as 24, of each fitting, is constructed to provide a lamp socket 25, and a groove 26 for the application 70 of a shade holder, as 27, and the arrangement permits of these parts being exposed upon the outside of the tubular support 12, without cutting or machining the wall of the tube further than to provide a 75 single round opening 28, for each lamp, as 10. To this end, the part 24 of each porcelain fitting 23 is formed with a shank or stem 29 adapted for introduction into the corresponding opening 28 from the outside 80 of the tube 12. This shank or stem may be provided with flat sides, as 30, Figs. 2 and 4, in which case a plate 31, having a correspondingly shaped central opening 32, is fitted over the shank 29 within the tube 12 to 85 prevent rotation of the fitting.

The other part, as 33, of each porcelain fitting 23, preferably takes the form of an inverted cup, adapted to be fitted over the shank 29 of the part 24 upon the inside of 90 the tube 12. A post 37 projects centrally from the bottom of the cup chamber and extends through an opening 38 in the shank 29 of the part 24 and into the lamp socket 25, when the two parts of the fitting 23 are assembled.

The side walls of the part 33 are notched, as at 34 to permit the passage of the electrical conductors 14, 15, and binding screws 35 and 36 are mounted within the cup chamber for engagement with said conductors. These binding screws are carried by separate insulated metal plates 39 and 41. The plate 39 extends into the post 37 from one side and is secured in place by means of a 100 screw 40 which extends centrally through the post 37 and constitutes the center contact for the lamp, as 10. The plate 41 is grooved to extend about the post 37 at the remote side of the same from the plate 39. 110 It is secured against the floor of the cup chamber by a pair of screws 42. A second

pair of screws 43 enter the plate 41 from within the lamp socket 25. These last mentioned screws serve both for uniting the two parts 24 and 33 of the fitting 23 and for 5 making the electrical connection between the plate 41 and the side contact 44, of the lamp socket.

In assembling the parts of the apparatus, the parts 33 of the several fittings 23 are 10 applied to the conductors 14, 15, and are then passed into the tube 12 from one end to register with the openings 28. Plates 31, also pass into the tube 12 from one end and are applied to the wall of the tube upon 15 the inside over the openings 28. The parts 24 of the fittings 23 are then applied to the openings 28 from the outside of the tube and the screws 43 are introduced for connecting the two parts of each fitting. Shade 20 holders, as 27, and lamps as 10, may then be applied to each fitting and when suitably supported in place the apparatus is ready for use upon the introduction of the plug 22 into a suitable socket (not shown).

25 The portions of the conductors, as 14, 15, from which the insulation has been removed for connection with the binding screws, as 35, 36, are completely covered and the construction permits of the parts being assembled at the factory for transportation and installation at the place of use as a one piece fixture. The employment of skilled labor for making the installation is therefore unnecessary while an efficient and workman-like construction is nevertheless obtained.

I claim as my invention,—

1. An apparatus for supporting and supplying current to a plurality of electric lamps comprising, in combination, an integrally walled flat sided metal tube having a separate opening in one of its flat sides for each lamp to be supported and otherwise imperforate, a porcelain fitting secured in each of said openings, each fitting being 40 constructed to provide a lamp socket opening upon the outside of the tube and wires extending through the tube for attachment to each of said fittings.

2. An apparatus for supporting and supplying current to a plurality of electric

lamps comprising, in combination, an integrally walled metal tube having a separate lateral opening for each lamp to be supported and otherwise imperforate, a porcelain fitting secured in each of said openings, 55 each fitting being constructed to provide a lamp socket opening upon the outside of the tube, and wires extending through the tube for attachment to each of said fittings.

3. An apparatus for supporting and supplying current to a plurality of electric lamps comprising, in combination, an integrally walled metal tube having a single lateral opening for each lamp to be supported and otherwise imperforate, a two 60 part porcelain fitting having its parts applied to the inside and the outside of the tube at each of the said openings, the part of each fitting which is applied to the outside of the tube being constructed to provide a lamp socket, clamping means uniting the two parts of each fitting, and wires extending through the tube for attachment to each fitting.

4. An apparatus for supporting and supplying current to a plurality of electric lamps comprising, in combination, an electric conductor, a plurality of two part porcelain fittings, one of the parts of each fitting being attached to the said conductor and the 65 said fitting parts which are attached to the conductor being located at intervals along the same, a tube inclosing the conductor and the last mentioned fitting parts, the wall of the tube being formed with lateral openings 70 which register with the inclosed fitting parts but each of which is of insufficient size to permit the corresponding fitting part to pass through the same and the tube being otherwise constructed to permit the introduction 75 of the said conductor and the fitting parts which are attached thereto only through the end of the tube, the other part of each fitting being applied to the outside of the tube at one of its said lateral openings and being 80 constructed to provide an outwardly facing lamp socket, and clamping means uniting the two parts of each fitting.

FREDERICK A. WATKINS.
